CLAIM

The ornamental design for a breath mint dispenser, as shown and described.

DESCRIPTION

FIG. 1 is a top, front, left side perspective view of a breath mint dispenser showing our new design;

FIG. 2 is a front elevational view thereof;

FIG. 3 is a back elevational view thereof;

FIG. 4 is a left side elevational view, with the right side elevational view being the mirror image thereof;

FIG. 5 is a top plan view thereof; and,

FIG. 6 is a bottom plan view thereof.
